(74) Attorney, Agent, or Firm—Fay, Sharpe, Fagan,
Minnich & McKee, LLP(57) **CLAIM**The ornamental design for a sportsball, as shown and
described.

DESCRIPTION

FIG. 1 is a front elevational view of a sportsball showing our
new design;

FIG. 2 is a right side elevational view thereof;

FIG. 3 is a rear elevational view thereof;

FIG. 4 is the left side elevational view thereof;

FIG. 5 is a top plan view thereof;

FIG. 6 is a bottom plan view thereof; and,

FIG. 7 is a front right perspective view thereof.

The portion of FIG. 6 shown in broken lines is for illustrative
purposes only; and forms no part of the claimed design.**1 Claim, 7 Drawing Sheets****FIG. 1**
